DESIGN FOR AN OIL BURNING COOK STOVE

William T. Bradbury, Kankakee, Ill., assignor to Florence Stove Company, Gardner, Mass., a corporation of Massachusetts

Application February 25, 1935, Serial No. 55,596

Term of patent 7 years

To all whom it may concern:

Be it known that I, William T. Bradbury, a citizen of the United States, residing at Kankakee, in the county of Kankakee and State of Illinois, have invented a new, original, and ornamental Design for an Oil Burning Cook Stove, of which the following is a specification, reference being had to the accompanying drawing, forming part thereof.

Figure 1 is a perspective view of an oil burning cook stove showing my new design.

Fig. 2 is an elevational view of one end of the stove, the other end thereof being substantially the same.

I claim:—

The ornamental design for an oil burning cook stove substantially shown and described.

WILLIAM T. BRADBURY.
